(57) **CLAIM**

The ornamental design for toy jet-plane launcher, as shown and described.

DESCRIPTION

FIG. 1 is a first perspective view of a toy jet-plane launcher showing my design;

FIG. 2 is a second perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a first perspective view of the toy jet-plane showing a status when the toy jet-plane launcher is being used;

FIG. 10 is a second perspective view of the toy jet-plane showing a status when the toy jet-plane launcher is being used;

FIG. 11 is an enlarged view of the toy jet-plane launcher in FIG. 1 of the region identified as "11" in FIG. 1;

FIG. 12 is an enlarged view of the toy jet-plane launcher in FIG. 1 of the region identified as "12" in FIG. 1;

FIG. 13 is an enlarged view of the toy jet-plane launcher in FIG. 2 of the region identified as "13" in FIG. 2;

FIG. 14 is an enlarged view of the toy jet-plane launcher in FIG. 3 of the region identified as "14" in FIG. 3; and,

FIG. 15 is an enlarged view of the toy jet-plane launcher in FIG. 3 of the region identified as "15" in FIG. 3.

The evenly-spaced broken lines illustrate portions of the toy jet-plane launcher that form no part of the claimed design; the additional evenly-spaced broken lines in FIGS. 9 and 10 illustrate environmental subject matter that form no part thereof; the dash-dot broken lines are for purposes of annotating the enlarged views and form no part of the claimed design.

1 Claim, 15 Drawing Sheets
